UNITED STATES PATENT OFFICE.

EDMUND SCHROEDTER, OF BROOKLYN, NEW YORK.

IGNITER-VALVE.

1,295,801.

Specification of Letters Patent. Patented Feb. 25, 1919.

Application filed June 10, 1918. Serial No. 239,238.

To all whom it may concern:

Be it known that I, EDMUND SCHROEDTER, a citizen of the United States of America, residing at Brooklyn, New York, have invented a new and useful Igniter-Valve, of which the following is a specification.

My present invention relates to the ignition of gas engines and consists broadly in utilizing the heat of the exhaust gases for igniting the subsequent charges within the engine.

In a preferred embodiment the invention comprises a hot tube igniter carried directly by the exhaust valve of the engine in such a way as to be subjected directly to the heat of the gases within the exhaust passage and exposed to the combustion chamber in such a way as to ignite the fresh charges when they have been brought to the proper degree of compression. According to one form this igniter is in the form of a relatively small tube seated in the head of the exhaust valve and having its interior open to the combustion chamber, said tube having a closed end portion projected below the head of the valve and extending into the exhaust passage.

Various other features of the invention will appear as the specification proceeds.

In the accompanying drawing I have illustrated the invention embodied in a practical commercial form, but with the understanding that the invention is not limited to this form and that various modifications and changes may be made without departure from the true spirit and scope of the invention.

In this drawing:

Figure 1, is a side elevation of a gas engine valve constructed in accordance with and embodying the invention.

Fig. 2, is a broken sectional view of the same.

Fig. 3, is a transverse sectional view taken substantially on the line 3—3 of Fig. 1.

Fig. 4, is a top plan view of the valve.

Fig. 5, is a more or less diagrammatic view of the valve as in use in an engine of the L-head type.

The valve illustrated is of the "puppet" type embodying a head 7 and a stem 8, said stem in this instance being forked at its upper end to provide a series of branches or arms 9 so as to leave an open space 10 within or between said arms and beneath the head of the valve.

11 designates the igniter here shown in the form of a relatively thin-walled tube seated in the valve head and secured therein by means of a screw threaded upper portion 60 12 engaged in a correspondingly threaded opening or seat 13 in the valve head, said tube being open at its upper end and extending down into the open space 10 between the forked arms of the valve stem, 65 the lower end of the tube being closed, as indicated at 14. The upper end of the tube is also shown formed with a tapered head portion 15 making a gas tight joint with the seat in which it is engaged and which for 70 the purpose is similarly tapered. Said head furthermore is shown provided with slots 16 to take the point of a screw-driver or other tool.

Up to the present, I have found it best 75 to construct the igniter tube as a relatively thin shell so as to readily take up the heat of the exhaust gases and therefore be maintained sufficiently hot for ignition purposes even when the engine is running slowly, and 80 to prevent warping or distortion, "scaling" or rapid wearing away of this relatively thin shell, I have so far found it best to construct this tube of nickel. This metal I have found is capable of withstanding the high 85 temperature of the exhaust gases without undue oxidization and without being injuriously affected thereby. Furthermore the ignition tube of substantially pure nickel possesses the peculiar property of retaining 90 sufficient heat to fire the compressed charges even after the cooling effect exerted on the tube by the contact of the freshly admitted relatively cooler charges therewith. This 95 high heat retentivity is particularly advantageous at slow engine speeds and is, I believe a new characteristic in this combination not possessed by nickel steel or other metals that I have tried for this purpose.

The operation of the device will be apparent from Fig. 5, wherein I have illustrated the valve as in place in an engine cylinder 17, said valve controlling in this instance the exhaust functions of the engine and coöperating for that purpose with an 100 exhaust valve seat 18 leading to the exhaust port or passage 19. Initially the engine may be started with independent or supplementary ignition means such as an electric spark plug as indicated at 20. The exhaust 105 gases quickly heat up the ignition tube, and as soon as said tube is brought to approxi-

mately a red heat the electrical igniter may be dispensed with as then the charges, as they are brought to the proper degree of compression, will be fired by the hot tube. 5 This tube, may as shown, be extended well down into the exhaust passage so as to receive the full heat of the exhaust gases trapped in the exhaust passage upon the closing of the exhaust valve. Also this hot 10 tube is designed, as to length, thickness of wall, depth of the pocket therein, etc., as to ignite the charge at the most effective period. By properly designing the tube, therefore, the ignition will be automatically maintained at the point of greatest efficiency, the 15 ignition being automatically advanced, due to the quicker heating, as the speed of the engine increases and being automatically retarded, as the tube heats slower, due to 20 decreased engine speed. With my invention, therefore, it becomes possible to control the engine solely by the throttle, the ignition being automatically controlled and maintained at the point of greatest efficiency by 25 conditions within the engine. The igniter tube has a tendency to clean itself and keep free of carbon deposits, etc., by reason of the fact that the propagation of the flame occurs at the hottest part, the bottom or 30 pocket in the lower end of the tube, this initial flame or explosion in the bottom of the tube tending to clean the tube of any foreign matter or possible carbon deposits.

My invention, it will be apparent, makes 35 the engine automatic or self-igniting and may be used as an auxiliary to the ordinary electric ignition system, or as above set forth, the electric ignition may be dispensed with as soon as the so-called "exhaust igniter" 40 becomes operative. In the case where the exhaust igniter is used in conjunction with, or as an auxiliary, to the electrical ignition system, this automatic igniter is of particular value in that it insures more rapid flame 45 propagation and ignition at the most efficient point and further, in that in case of failure of the electric ignition system the engine will continue to run under the automatic ignition. The electrical ignition apparatus may be dispensed with by providing 50

suitable electrical connections for initially heating the ignition tube. This may be accomplished by connecting the tube temporarily in circuit at starting in such a way as to cause the current to longitudinally 55 traverse the tube, the resistance effect being sufficient to heat the tube enough to fire the charge.

I claim:

1. In a gas engine, a puppet valve including a valve head and a stem connected thereto, said valve stem being connected to the valve head by forked arms to thereby provide an open space within said arms and beneath the valve head and an igniter element mounted in the valve head and having a dependent portion disposed within said open space between the forked arms of the valve stem. 60

2. In a gas engine, an exhaust valve comprising, a valve head and a valve stem having forked arms connected with said head, said forked arms being disposed within the exhaust port of the engine and an igniter element carried by the valve between said 65 forked arms and exposed to the gases of combustion within said exhaust port. 70

3. The combination with a gas engine exhaust valve, of an ignition tube disposed in the path of flow of the exhaust gases past 80 said valve and exposed also to the freshly admitted charges, said ignition tube being of substantially pure nickel of high heat retentivity and thereby capable of firing the compressed charges following the cooling effect exerted thereon by the admission 85 of the fresh relatively cool charges into contact therewith. 90

4. A gas engine exhaust valve comprising a valve head and an ignition tube carried by 90 said valve head in the path of flow of the exhaust gases past said valve and exposed also to the freshly admitted charges, said ignition tube being of substantially pure nickel of high heat retentivity and thereby 95 capable of firing the compressed charges following the cooling effect exerted thereon by the admission of the fresh relatively cool charges into contact therewith.

EDMUND SCHROEDTER.
